SIGNAL PISTOL

Marshall G. Coulter, 118 Park St., Tecumseh, Mich.
Filed Apr. 5, 1963, Ser. No. 270,996
4 Claims. (Cl. 42—1)

The present invention relates to a signal pistol.

It is an object of the present invention to provide a signal pistol which is simple in construction and efficient in use.

It is another object of the present invention to provide a signal pistol which is relatively inexpensive to manufacture.

It is another object of the present invention to provide a signal pistol which includes an improved firing mechanism.

In the drawings:

FIG. 1 is an elevational midsection of a signal pistol embodying the present invention.

FIG. 2 is a sectional view of the complete pistol taken along the line 2—2 in the direction of the arrows, FIG. 1.

Referring to the drawings, a barrel section is indicated by the number 7. The barrel section is pivotally connected to a handle section 9 by the dowel 11.

The barrel section 7 includes the combined barrel and chamber portion 13 which is adapted to accommodate a shell or cartridge type signal flare. The groove 15 is formed to receive the flange on the flare shell (not shown).

A guide pin passage 17 is provided in the barrel section 7, and a coil spring 19 is positioned in the passage. A guide pin 21 is disposed in the passage 17 adjacent the spring 19, and is movable in said passage. A breech lock pin 23 is affixed to the free end of guide pin 21, and is slidably in a breech lock pin groove 25 extending between the barrel section 7 and the handle section 9. A shoulder 27 overlies the breech lock pin 23 in the locked position. An opening 29 is positioned above the groove 25 and permits movement of the breech lock pin 23 upward when it is out from under shoulder 27. Thus by moving the breech lock pin 23 to the left in the drawings, the breech is unlocked and the barrel section 7 may be pivoted around dowel 11 relative to the handle section 9. In this manner, loading and unloading of the pistol can be accomplished.

A firing pin passage 31 extends through the handle section 9 to house a firing pin 33. The inner end of passage 31 is reduced at 35 to accommodate the end 37 of the firing pin. A coil spring 39 is positioned in the firing pin passage 31 between the firing pin 33 and the inner end of the passage. The outer end of the firing pin 33 extends out of the passage 31 and is affixed to a cocking knob 41. A spring 43 is seated between the enlarged section 45 of the firing pin and a washer 47 which is press fitted into the outer end of the firing pin passage 31 in a suitable washer groove. A peripheral substantially V-shaped cocking groove 48 is located in the enlarged section 45 of the firing pin.

A substantially vertical locking pin passage 49 extends from the top of handle section 9 downwardly to intersect a trigger passage 51. A locking pin 52 is slidably disposed in said passage 51 and has a tapered top end. The bottom end is also slightly tapered. The trigger passage is enlarged near its forward end. A trigger button 53 is slidably disposed in the forward end of trigger passage 51, and seats against a coil spring 55. The main shaft 57 of the trigger extends into the rear portion of trigger passage 51 and has a flange 59 formed thereon. Also provided on the trigger shaft 57 are a first step portion 61 and a second step portion 63.

A safety clasp is provided at 65. It is formed of spring wire, and has legs 67 and 69 which are disposed in the

2

handle section 9 with an interference fit. An offset firing pin rod seat 71, which is slightly smaller in diameter than the firing pin rod, is formed in the clasp 65. The interference fit of the legs 67 and 69 assures that the clasp will stay in the position to which it is set. FIG. 1 shows the safety clasp in the "off" position, and FIG. 2 shows the safety clasp in the "safety" or "on" position.

Operation

- 10 In operation, the device is used as follows: The breech lock pin 23 is moved to the left, and the breech is opened as the barrel section 7 is pivoted in a counterclockwise direction around the dowel 11. A signal cartridge is inserted into the barrel 13, and the breech is closed, the breech lock pin 23 being urged into place under the shoulder 27 by the spring 19 and guide pin 21. The cocking knob 41 is moved to the right against the spring 43 until the cocking groove 48 is positioned over the tapered upper end of locking pin 52. The spring 43 is of such dimension that the cocking groove 48 is over the locking pin 52 when the spring 43 is compressed. At this point the locking pin 52 may move upward into the cocking groove 48, and the trigger spring 55 moves the trigger forward so that the bottom of the locking pin 52 is on the first step 61. This moves the locking pin 52 upward so that its upper end seats in the cocking groove 48 on the firing pin 33. The tapered configuration of the cocking groove 48, the upper and lower ends of the locking pin 52, and portion of the trigger between steps 61 and 63 aids in the desired movement of locking pin 52.
- 20 The safety clasp may now be moved downward into the position shown in FIG. 2 if desired. However, if it is desired to fire the pistol, then the trigger button 53 is moved into the handle section 9 against the spring 55. This moves the second step 63 under the lower end of the locking pin 52, and the locking pin 52 moves downward and out of the cocking groove 48. When this happens the spring 43 moves the firing pin 33 to the left against cushioning spring 39 and the end 37 of firing pin 33 moves through passage 35 into engagement with the firing cap of the flare shell (not shown).
- 25 The pistol is characterized by its simple and easy-to-operate construction.
- 30 Having thus described my invention, I claim:
- 35 1. A signal pistol adapted to fire a signal flare, comprising:
- 40 a barrel having a flare chamber therein;
- 45 a handle pivotally connected to said barrel;
- 50 a firing pin passage in said handle having a spring loaded firing pin therein extending rearwardly and outwardly therefrom, said firing pin having a cocking knob on its rearward end external of said handle, and also having a cocking groove thereon which provides a cam wall that is movable inside said firing pin passage;
- 55 a trigger passage in said handle below said firing pin passage and having a trigger spring therein;
- 60 a trigger disposed in said trigger passage against said spring, which urges said trigger forwardly out of said trigger passage;
- 65 a first step on said trigger, and a lower second step ahead of said first step on said trigger;
- 70 a locking pin passage in said handle extending between said firing pin passage and said trigger passage; a floating locking pin slidably positioned in said locking pin passage; and a cam surface on the top of said locking pin engageable with the cocking groove cam wall on the firing pin;
- 75 the device being cocked by pulling the cocking knob back until the cocking groove cam wall in the firing pin overlies the top of the locking pin, at which point

the trigger spring moves the first trigger step under the bottom of the locking pin and engages the cam surface on the top end of the locking pin with the cocking groove cam wall; and the device is fired by moving the trigger in toward the handle, which action moves the second step beneath the bottom of the locking pin in place of the first step and enables the spring loaded firing pin to move the locking pin out of the cocking groove.

2. A signal pistol according to claim 1 wherein safety means is provided on said handle, said safety means being movable to a position between the rear of the handle and the cocking knob in the safety position.

3. A signal pistol adapted to fire a signal flare, comprising:

a barrel having a flare chamber therein; a handle pivotally connected to said barrel; a firing pin passage in said handle having a spring loaded firing pin therein extending rearwardly and outwardly therefrom, said firing pin having a cocking knob on its rearward end external of said handle, and also having a substantially V-shaped cocking groove thereon which provides a cam wall that is movable inside said firing pin passage;

a trigger passage in said handle below said firing pin passage extending substantially parallel to said firing pin passage and having a trigger spring therein; a trigger disposed in said trigger passage against said spring, which urges said trigger forwardly out of said trigger passage;

a first step on said trigger, a lower second step ahead of said first step on said trigger, and a cam portion extending between said first and second steps; a locking pin passage in said handle extending between said firing pin passage and said trigger passage; and a floating locking pin slidably positioned in said locking pin passage, said locking pin having a tapered upper end and a tapered lower end;

the device being cocked by pulling the cocking knob back until the cocking groove cam wall in the firing pin overlies the top of the locking pin, at which point the trigger spring moves the first trigger step under the bottom of the locking pin and engages the tapered top end of the locking pin with the cocking groove cam wall; and

the device is fired by moving the trigger in toward the handle, which action moves the trigger cam portion and then the second step beneath the bottom of the locking pin in place of the first step and enables the spring loaded firing pin to move the tapered top end of the locking pin out of the cocking groove.

4. A signal pistol adapted to fire a signal flare, comprising:

a barrel having a flare chamber therein;

a pistol grip handle pivotally connected to said barrel; a firing pin passage in said handle extending in the same direction as said barrel in the firing position; a spring loaded firing pin in said firing pin passage and extending rearwardly and outwardly therefrom, said firing pin having a cocking knob on its rearward end external of said handle, and also having a cocking groove thereon which provides a cam wall that is movable inside said firing pin passage; a trigger passage in said handle below said firing pin passage extending substantially parallel to said firing pin passage and having a trigger spring therein; a trigger disposed in said trigger passage against said spring, which urges said trigger forwardly out of said trigger passage;

a first step on said trigger, and a lower second step ahead of said first step on said trigger;

a locking pin passage in said handle extending from the top of the handle to the firing pin passage and from the firing pin passage downwardly to the trigger passage;

a floating locking pin slidably positioned in said locking pin passage between said firing pin passage and said trigger passage; and

a cam surface on the top of said locking pin engageable with the cocking groove cam wall on the firing pin;

the device being cocked by pulling the cocking knob back until the cocking groove cam wall in the firing pin overlies the top of the locking pin, at which point the trigger spring moves the first trigger step under the bottom of the locking pin and engages the cam surface on the top end of the locking pin with the cocking groove cam wall; and

the device is fired by moving the trigger in toward the handle, which action moves the second step beneath the bottom of the locking pin in place of the first step and enables the spring loaded firing pin to move the locking pin out of the cocking groove.
